FLOW METER

Gerald L. Rogers, Olivette, Mo., assignor to Stile-Craft Manufacturers, St. Louis, Mo., a corporation of Missouri

Application June 20, 1957, Serial No. 46,672

Term of patent 14 years

(Cl. D52—1)

Figure 1 is a top plan view of a flow meter showing my new design;

Figure 2 is a front elevational view thereof;
Figure 3 is a side elevational view thereof;

Figure 4 is a side elevational view thereof, looking at the other side; and

Figure 5 is a rear elevational view thereof.

I claim:

The ornamental design for a flow meter, as shown.
